HANS CHRISTIAN BJERING, OF GJOVIK, NORWAY

HIGH-PRESSURE-STEAM BOILER

Application filed June 17, 1927, Serial No. 199,608, and in Germany January 25, 1927.

The present invention relates to high pressure steam boilers and particularly to the type of such boilers wherein the heating surface and also the water contents are small in relation to the output. Therefore, the ordinary motion of the flue gases past the steam generating elements by means of stack draught or by a blast at the air inlet will prevent the obtaining of a satisfactory efficiency. 10 Among other difficulties in such boiler plants should be mentioned the danger existing for accidents caused by a rupture in the boiler.

The purpose of the present invention is to avoid these inconveniences by a special arrangement of the course of the heat before it reaches the open air or the stack and also by a special construction of the boiler.

According to the invention I use as a fuel for the boiler a gas produced in a closed system in the fire chamber of the boiler. For instance combustible oils may be volatilized whereupon the obtained gas is mixed with air and is then passed into chambers or passages, wherein it is under pressure beneath a grate, the purpose of which is to distribute the combustible gas uniformly and directly to the steam generating elements and to prevent a back-throw or a return flow of the gases expanding during their combustion. 30 The grate should for this purpose be comparatively thick and have a large area as compared with the apertures or slots passing therethrough.

During the combustion above or on the top surface of the grate, the volume of the gases of combustion will highly increase, whereby a static pressure is created which, as a back-throw of the gases through the grate cannot take place, will result in the gases, being 40 without any draught, forced forwards in the fire chamber, wherein the steam generating elements are arranged. On account of a sort of gas seal which the gases must pass before reaching the outlet (stack), the heat within 45 the fire chamber will be distributed quite uniformly throughout the heating surface of the boiler, and as a consequence thereof the gases will give off the most possible heat to the boiler. In the fire chamber, in addition to 50 the generating elements, may also be ar-

ranged a superheater, and in the seal, a preheater may be arranged which will be heated in the same uniform manner as the remaining parts of the boiler.

In this firing method the seal has to fulfill four purposes, viz:

1. To ensure a quite uniform heating of the whole boiler, whereby strains of material between its several parts or members and also dangers for leakages are avoided. It is a wellknown fact that high pressure boilers with small water contents are much liable to get short of water and consequently to become red-hot, but as a consequence of the uniform heating all over in connection with the special construction, the present boiler will be able to stand this taking place even under pressure.

2. To utilize the heat to the most possible degree for generation of steam, for superheating and for preheating purposes as a cause of the gases of combustion being pressed against the seal and being forced to fill up all free space before reaching the open air, so that the steam generating elements and the other members will be swept over by the gases in a more efficient manner than in case of any sort of draught.

3. To prevent unnecessary heat to escape through the stack when the fire is out of operation. This being very important in case the firing takes place with interruptions.

4. To reduce the corrosion of the boiler surface, because oxidizing air at the end of the firing operation is prevented from finding its way into the fire chamber.

The boiler proper is provided at its upper portion with a steam header or collecting pipe and at its bottom with a water header or water collecting pipe. Between these headers the steam generating or boiler elements are arranged. In order to reduce the danger of explosions the connecting passages between the headers and the boiler elements are made in the form of narrowed pipes adapted to form a resistance to the outflow from the elements in case one of them should be subject to a rupture. Thereby the outflow through the rupture will lose its explosive character.

In boilers of the kind referred to it is of

great importance to avoid sediments of possible impurities. In the present case such sediments or mud collections on account of the peculiar arrangement of the boiler elements, will sink down and settle into a water header of a comparatively small diameter, wherefrom they can be blown out by means of the steam pressure. However, in order to prevent the impurities from burning fast within the header pipe, this pipe should be so arranged that its underside is not subjected to the direct influence of the flue gases.

All the purposes mentioned above are realized in the present boiler construction illustrated in the annexed drawing.

Figure 1 is a vertical section through the fire chamber and one boiler element showing also steam and water headers arranged in accordance to the invention.

Figure 2 is a side elevation showing a number of boiler elements connected at top and bottom to headers in the manner indicated above.

Figure 3 is a plan view of a portion of a group of boiler elements arranged side by side in one and the same plane.

Figure 4 is a plan view showing a portion of a group of elements arranged side by side so as to form a ring.

Figure 5 is a sectional plan view looking down on the grate in Figure 1.

In the drawing, 1 denotes the brickwork, 2 the fire chamber, into which the combustible mixture of gasified fuel and air is introduced by a suitably high pressure beneath the grate 3. This grate is arranged alongside the boiler elements 5 and is of a suitable width. It consists of a perforated plate, and the perforations may be cylindrical or tapered or in case in the form of slots, but at all events they should be small or narrow as compared with the thickness and the superficial area of the grate. 4 denotes a sloping face, whereby the flame is forced in a direction against the boiler elements 5. The gases of combustion will thereby be caused to sweep around the elements 5 giving off their essential part of heat to the said elements and then passing to the seal 6 and finally on to the stack 7. Preheaters or economizers may, if desired, be arranged in the seal 6, and in the fire chamber superheaters (not shown) may be arranged in addition to the steam generating elements 5. These elements 5 are connected through comparatively narrow pipes 8 with a pipe forming a header or collector for the boiler water, and the elements are through similar narrow pipes 10 connected with a pipe 11 forming a steam header.

The water header 9 is so arranged that sediments or heavier impurities contained in the water will collect therein. In order to avoid the damage which might follow from such sediments being burnt fast to the boiler walls, the water header 9 is so arranged in relation

to the grate 3 that it cannot be swept on its underside by the flame.

During the combustion the gases will rise in temperature and consequently their volume will be considerably increased. The result will be that the gases obtain an expansive pressure tending to force them away from the chamber above the grate, but on account of the over-pressure beneath the grate and the special construction of the latter, a forcing-back will be excluded and, even if no other measures are taken to produce a draught, the gases will be forced by the pressure of expansion to pass by the boiler elements 5 and out into seal 6 and stack 7, after having given off the most part of their heat to the elements 5. The gases arrive into the stack without any considerably high temperature.

By the cooling the gases of combustion will again decrease in volume, and it is therefore possible to make the channels with successively decreasing cross section without increasing their velocity. This may preferably be obtained by arranging the elements 5 in a ring and causing the gases to pass through concentric channels, toward the central part of the boiler, where the stack is located. A reduction of the dimensions of the boiler system is thereby obtained.

If for some reason a boiler element should crack, it might be supposed that a great accident would happen, especially on account of the high steam pressure prevailing in the boiler. Such a thing will not take place however, because in the narrowed connecting pipes 10 between the elements the steam will meet a high frictional resistance and, in addition, will be subjected to losses due to shocks, whereby the living force of the outflowing steam will be of no danger.

The arrangement shown possesses the advantage that the construction can be standardized, because boiler elements of the same dimensions can be used to build up boilers of different capacity, the latter being simply varied by the number of elements and by arranging the elements in one or more rows or groups.

According to Figs. 1 to 3 the boiler elements are presumed to be located along one and the same plane. Fig. 4 shows elements arranged as a curved row, the stack being arranged in the central part inside such a circular row. Obviously other modifications can be made without departing from the spirit of the invention.

Claims:

1. A high pressure boiler with small water content, comprising an air and fuel mixing combustion chamber, a combustion gas distributing grate, steam generating elements in said chamber and placed along the passage of the combustion gases, a stack and a seal establishing communication between the combustion chamber and the stack and caus-

ing a resistance to the movement of the gases so as to obtain an equal distribution of the heat in the heating chamber, a fuel chamber below the grate, and means to supply the same with a mixture of gasified fuel and air under high pressure, the said grate having perforations of small cross sectional area in relation to the total grate area and permitting controlled passage of the mixture to the combustion chamber.

2. Apparatus of the class described, comprising a structure forming a fuel chamber, a combustion chamber above the fuel chamber, a stack in rear of the combustion chamber and walls forming a seal establishing communication between the upper end of said combustion chamber and the lower end of said stack, one of said walls forming also the rear side of said combustion chamber, said wall overhanging the lower portion of the combustion chamber and having a downwardly and rearwardly inclined diverting surface, a grate between the fuel chamber and the bottom of the combustion chamber and also overhung by said wall and said inclined surface of said wall and a steam generator in the front portion of said combustion chamber, entirely contained in said combustion chamber and opposite said wall.

3. In a high pressure boiler with small water content, the combination with a fire chamber containing steam generating elements positioned along-side on the wall of said chamber, of a fuel chamber, to be supplied with a mixture of gasified fuel and air, a grate separating the fuel chamber from the fire chamber, located alongside the said steam generating elements, a stack and a gas seal between stack and fire chamber and providing a resistance of the outflow of the combustion gases expanded by the combustion occurring in the fire chamber.

4. In a high pressure boiler with small water content, the combination with a fire chamber containing steam generating elements arranged along-side one wall of said chamber, of a fuel chamber, to be supplied with a mixture of gasified fuel and air, a grate separating the fuel chamber from the fire chamber located alongside the said steam generating elements, the said fire chamber having a wall arranged opposite the above-named wall and provided with parts overhanging the grate and spaced from the generating elements for directing the stream of combustion gases in contact with said elements, a stack, and a gas seal arranged between stack and fire chamber and providing a resistance to the outflow of the combustion gases expanded by the combustion taking place in the fire chamber.

In testimony whereof I affix my signature
HANS CHRISTIAN BJERING.
